LEVER GUIDE FOR FLUSH TANKS

Samuel Gertz, Jamaica, N. Y.

Application July 7, 1945, Serial No. 603,693

3 Claims. (Cl. 4-67)

1

This invention relates to flush tanks such as are used with water closets. With such tanks it is usual to provide a valve commanding a water outlet at the bottom of the tank and the valve is opened by a connection extending to a lever in the tank above the valve. This invention relates more especially to the valve-operating mechanism.

It is an object of the invention to provide improved guide means for the valve-operated lever of a flush tank. While the invention is not limited to water closet flush tanks, it does relate to that type of tank in which a ball, or valve of similar character, is moved down by gravity to close an opening in the bottom of the tank, and in which the valve is lifted by a connection with a lever extending lengthwise in the tank above the valve.

Such levers in the prior art have been guided in some constructions by their fulcrum bearings only, and in some other constructions by guides that were part of the lever-supporting structure that included the fulcrum. With these constructions, binding or sticking of the valve or its operating-connection, with the valve in open position, is often experienced after the apparatus has been in use for a considerable period, or after a worn valve has been replaced. The reason for the binding has not been apparent. The parts operate in water and therefore have no adequate lubrication. They wear and there is often some corrosive effect even though non-ferrous metals are used. By smoothing off rough places and aligning parts, binding and sticking can be eliminated and the valve made to seat properly, but the correction proves to be only temporary, and the fact that sticking and leaking of the valve is often intermittent makes diagnosis of the causes more difficult.

It is another object of this invention to provide valve operating means guided from the sides of the tank so that the lever which lifts the valve always moves up and down in the same relative location above the valve, and with this kind of guidance for the lever other causes of binding and sticking, such as roughening and corrosion of parts, and uneven wear of sliding members, do not, by themselves, cause sufficient friction to prevent the valve from closing properly.

In one embodiment of the invention guide means secured to the lever extend across the full width of a conventional tank so that any substantial lateral displacement of the lever is prevented by contact of the guide means with the sides of the tank. Another embodiment of

2

the invention provides a special tank construction with confronting side walls closely spaced at one end of the tank so as to provide, in effect, a guiding groove in which the end of the valve operating lever moves.

Other objects, features and advantages of the invention will appear or be pointed out as the description proceeds.

In the drawings, forming a part hereof, in which like reference characters indicate corresponding parts in all the views,

Figure 1 is a top plan view of a flush tank with the cover removed to show the valve-operating mechanism within the tank.

Figure 2 is a front view of the tank shown in Figure 1, mostly broken away and in section, but with the cover in place.

Figure 3 is a sectional view taken on the line 3-3 of Figure 1 with the cover on the tank.

Figures 4 and 5 are fragmentary detail views showing two different modifications of the invention.

The drawing shows a flush tank 10 with an opening in its bottom for the discharge of liquid from the tank. A pipe 12 extends through the opening in the bottom of the tank and is clamped in position by nuts 14 threaded on the end of the pipe 12. These nuts 14 clamp gaskets 16 against the inside and outside surfaces of the tank around the outside of the pipe 12 to prevent leakage from the tank.

A valve 18, which has a hemispherical face that fits into the open end of the pipe 12, controls the discharge of liquid from the tank 10.

A valve stem 20 is secured at its lower end to the valve 18 and has a hook at its upper end for engaging a link 21 that connects the valve stem 20 with an operating lever 22. The valve stem 20 passes through a fixed guide 23. Such guides are usually connected to an overflow pipe which extends up from the bottom of the tank and which connects with the outlet pipe 12. An illustration of such structure is not necessary for a full understanding of this invention.

The operating lever 22 is supported at one end on a stud 24 that serves as the fulcrum of the lever 22. This fulcrum is a part of a supporting structure connected to the upper front portion of the tank. The supporting structure includes a bushing 26 which extends through the front wall of the tank and is clamped in place by a clamping nut 27. The stud 24 extends through the bushing 26 and turns in this bushing as a bearing.

A handle 28 is rigidly connected to the forward

end of the stud 24 and the portion of the stud that extends through the end of the operating lever 22 is of square, or other noncircular cross section. The opening through the end of the operating lever 22 is of similar noncircular cross section so that when the handle 28 is moved to impart angular movement to the stud 24, the operating lever 22 will be moved through a similar angle.

Movement of the handle 22 from the solid to the dotted line positions shown in Figure 2 causes the operating lever 22 to be raised into the dotted line position shown; and this movement of the operating lever lifts the valve 18 and permits the liquid contents of the tank 10 to flow out through the pipe 12. When manual pressure on the handle 28 is released, the weight of the valve 18, lever 22 and connected parts causes the valve 18 to return to closed position.

It is important to maintain the operating lever 22 in correct relation to the valve 18 and the motion transmitting connections through which the operating lever 22 lifts the valve 18. Guiding of the operating lever 22 has been done in the prior art from the supporting structure that includes the fulcrum at the end of the operating lever remote from the valve.

Any reasonably close guiding of the operating lever 22 in the region of its fulcrum requires bearing means with close tolerances because play is multiplied at the valve end of the lever as a result of the length of the lever. Any support having close tolerances at the fulcrum end of the lever introduces the danger of binding which will prevent the lever 22 from moving freely. Guide means for the valve 18, which are sufficiently close to offset misalignment between the valve and the plane of movement of the end of the operating lever 22 that lifts the valve, also introduce danger of binding so that the valve 18 does not drop back into closed position freely. When the valve 18 is guided by a bearing through which the valve stem 20 passes, the danger of binding is increased by the fact that the bearing in the guide 23 is necessarily short.

This invention guides the operating lever 22 by guide means located toward the valve end of the lever. This locates the guide means at the end where the guiding is required and permits the use of guide means in which free movement can be obtained without having lateral clearances multiplied by the length of the operating lever. The guide means in the construction shown in Figures 1 to 3 include guide elements 31 and 32 which extend through openings in the operating lever 22, near the valve end of this lever.

Each of the guide elements 31 and 32 has a threaded end with clamping nuts 34 screwed tightly against opposite sides of the operating lever 22 for holding the guide element in position. The guide element 31 extends from one side of the operating lever 22 to the confronting side of the tank 10; and the guiding element 32 extends from the operating lever 22 to the inside face on the other side of the tank. These guide elements 31, 32 have rounded or curved ends so that they will slide freely along the sides of the tank even though the sides are not entirely smooth.

The guide elements 31 and 32 are individually adjustable, by turning the nuts 34, to locate the operating lever 22 so that its free end extends across the line of movement of the valve element 18. These guide elements 31 and 32 are adjusted to permit a limited transverse play of the operat-

ing lever 22 so that there is no danger of the ends of the guide elements binding against the sides of the tank if the tank width is not entirely uniform.

Figure 4 is a top plan view and shows a modified construction in which a valve-operating lever 36 is provided with guide elements 38 and 39 that are made as an integral part of the operating lever 36. Such a construction is not adjustable. Small variations in tank widths can be compensated for by filing or grinding off the ends of the guide elements 38 and 39, and these ends are shaped to provide a rounded surface for sliding in the inside surfaces of the tank 10.

Figure 5 shows another modified form of the invention in which an operating lever 42, corresponding to the lever 22 of Figures 1 to 3, is made long enough to extend into the space between guide ridges 44 which are formed on the inside end face of a flush tank 45. Except for the guide ridges 44, the tank 45 is of similar construction to the flush tank 10 shown in the other figures.

If the operating lever 22 is loosely connected with the stud 24, the lever has a transverse sag because of the fact that the lever is offset and its center of gravity is at a substantial distance beyond the end of the bearing provided for the lever on the stud. Advantage can be taken of this transverse sagging by providing a guide 32 or 39 on the front side of the operating lever only, with the guide of such length that it takes up at least a part of the transverse sag on the lever 22. With such a construction the sag of the operating lever provides a bias that makes the rearward guides unnecessary.

The preferred embodiment and some modifications of the invention have been illustrated and described, but other modifications can be made, and some features of the invention can be used without others without departing from the invention as defined in the claims.

I claim as my invention:

1. In a flush tank having side walls and a bottom with a discharge opening in the bottom of the tank commanded by a valve that is operated by a lever extending lengthwise of the tank above the valve, the combination with said lever of a fulcrum supporting one end of the lever adjacent an end of the tank, and guide means connected to the lever near its end remote from the fulcrum and extending transversely from both sides of the lever into close proximity to opposite sides of the tank so that contact of said guide means with the sides of the tank prevents any substantial transverse displacement of the lever.

2. In a flush tank having side walls and a bottom wall with an opening for the discharge of water from the tank, a valve element having a spherical surface that fits into the opening for closing said opening against discharge of water from the tank, a support connected to one side of the tank and having a stud extending into the tank, a lever supported by said stud and movable on the stud as a fulcrum, said lever extending lengthwise in the tank and across the top of the valve, a connection from the lever to the valve for raising the valve away from opening in the bottom of the tank, a manually operated device in the region of the fulcrum for moving the lever to open the valve, a guide having a threaded end that extends through the lever near the end of the lever remote from the fulcrum, nuts on the threads of the guide on opposite sides of the lever for obtaining adjustment

of the guide transverse of the lever, a similar guide with one end extending through the lever and the other end reaching to a point adjacent the back wall of the tank, and rounded ends on both of the guides for contact with the sides of the tank in the event of transverse displacement of the lever.

3. The combination with a flush tank of a valve at the bottom of the tank, a lever that extends lengthwise of the tank above the valve, a link extending from the valve up to the lever for lifting the valve to empty the tank, a lever-supporting element attached to the tank near one end of the lever and including a fulcrum for the lever, guide structure rigidly connected with the lever and located at a region remote from the lever-supporting element and the fulcrum, said guide structure having surfaces confronting and adja-

cent to inside surfaces of the tank that are on opposite sides of the guide structure and that prevent transverse movement of the lever toward either side during the movement of the lever about its fulcrum.

5 SAMUEL GERTZ.
